SURGICAL COT

Julia S. M. Knox, Richmond, Va., assignor of one-half to L. Ray Temple, Richmond, Va.

Application July 7, 1943, Serial No. 493,771

5 Claims.

(Cl. 5—317)

This invention relates to cots designed primarily for use in field hospitals, surgical wards, etc.

An object of the invention is to provide a cot of new and novel construction to be used as an attachment for a bed, the cot being so constructed that, when not in use, it can be stored beneath the bed but, when in active position, can be utilized as a temporary support for a patient while the bed is being changed or as a surgical table on which emergency operations can be performed conveniently.

A still further object is to provide a cot which, while still connected to the bed, can be moved to different positions relative to the bed so as to bring the patient thereon into position where daylight can be utilized most advantageously.

A further object is to provide a structure of this character which can be attached readily to beds of standard width and, because of its compactness and light construction, can be conveniently transported.

A still further object is to provide a surgical cot which can be quickly set up and connected to a hospital bed, thus making it especially useful in field hospitals and at other places where quick action is desirable.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawings the preferred form of the invention has been shown.

In said drawings

Figure 1 is a side elevation showing the cot assembled with and located close to one side of a bed, positions to which some of the parts can be adjusted being indicated by broken lines.

Figure 2 is a bottom plan view of the structure and of a portion of the bed to which it is joined, the legs of the bed being in section and some of the parts of the cot being shown by broken lines in positions to which they may be adjusted.

Figure 3 is a section on line 3—3, Fig. 1.

Figure 4 is an enlarged section on line 4—4, Fig. 2.

Figure 5 is an enlarged section on line 5—5, Fig. 1.

Figure 6 is an enlarged section on line 6—6, Fig. 2.

Figure 7 is an enlarged section on line 7—7, Fig. 1.

Figure 8 is a section on line 8—8, Fig. 1.

Figure 9 is an enlarged section on line 9—9, Fig. 2.

Referring to the figures by characters of reference, 10 designates the rigid frame of the cot which can be made of any suitable material and supports a top 11 which can be in the nature of a flat board to one end of which is hingedly connected another board 12 constituting the head section of the cot. This head section when in its lowermost position, extends to one end of the frame 10. The opposite end of the board 11 is recessed as at 13 so as to provide at its sides, forwardly extending arms 14. To each of these arms is bolted an ear 17 extending backwardly from the upper end of a tubular hanger 18, this hanger being supported beyond the forward end of wing 14 and constituting a bearing for a stem 19. The upper end of this stem, which is located above hanger 18 and in front of the adjacent arm 14, has an eye 20 extending into the forked end 21 of a leg-rest 22. This rest is preferably in the nature of a rigid flat strip of material of sufficient width to properly support one of the legs of the patient. The leg-rest is connected to the eye 20 by a pivot pin 23 seated in the leg-rest and extending through the eye. Thus it will be noted that the leg-rest is free to swing upwardly from a horizontal position relative to the stem 19 and to the cot top 11 while, at the same time, it is free to swing laterally relative to the top 11 as indicated, for example, by broken lines in Fig. 2.

Fixedly secured to the lower end of the stem 19 so as to turn therewith, is a bracket 24 having a slotted head 25 in which is slidably mounted a longitudinally slotted segment 26 fixedly secured at one end to one of the leg-rests, as indicated at 27. A clamping bolt 28 is extended through the slotted segment 26 and the head 25 and is engaged by a nut 29 which, when tightened, will cause the bolt to bind against segment 26 and hold it and the leg-rest against up and down swinging movement. Thus the leg-rest can be adjusted angularly in a vertical plane relative to the top 11 and secured in that position by tightening the nut 29. Thereafter the leg-rest can be swung about the longitudinal axis of the stem 19 and following this latter adjustment, the stem can be held against rotation by a set screw 30 carried by the hanger 18.

When the leg-rests are in their normal positions they are parallel and in the same plane

with the top of the cot. When they are swung upwardly and adjusted apart, ample room is provided therebetween to receive the doctor or surgeon working on the patient, the area being increased by forming the recess 13 in the forward end of the top 11.

The head section of the cot has longitudinally slotted segments 31 fixedly secured to the sides thereof and extending downwardly therefrom, these segments being concentric with the axes of the hinges 32 connecting the head section to the top 11 and both segments 31 slide upon clamping bolts 33 extending laterally from frame 10 and carrying clamping nuts 34. Thus the head section 12 can be adjusted angularly upwardly or downwardly and securely held in any position to which it may be moved.

Connecting the sides of the frame 10 adjacent to the two ends of the top 11 are cross-strips 35, one of the cross-strips being located preferably beneath the head section 12 although not connected thereto. To each of these cross-strips 35 is bolted the tubular upper section 36 of a leg, this upper section preferably being formed with oppositely extending ears 37 through which attaching bolts 38 are extended into the strips 35. The lower section 39 of the leg telescopes into the upper section 36 and is provided at its lower end with a caster 40 adapted to roll in any direction freely on a supporting surface. The two sections of the leg are held against relative rotation in any suitable manner, as by means of a rack 41 on the leg section 39 and slideable in a longitudinal groove 42 in the upper leg section 36. Each of the upper leg sections has a pawl 43 pivotally mounted therein and provided with teeth 44 adapted to engage the teeth of the adjacent bracket 41 so that when the parts are in engagement it becomes impossible for the upper member 36 to slide downwardly on the lower member 39. Such action can take place only by lifting the member 36 slightly relative to the member 39, swinging the toothed pawl 43 upwardly by depressing its handle or lever 45 so as to disengage the teeth of the cam from the rack. This is shown in Fig. 8 wherein the cam is shown by full lines in locking position and by broken lines in releasing position.

Attention is called to the fact that the two legs constituting supports for the cot are located along the longitudinal center line of the cot so that a load placed on the cot will be transmitted to these legs which thus will serve to properly support the load as long as its balance is maintained.

For the purpose of connecting the cot to a bed and at the same time preventing the cot from overturning on its two supporting legs, there is provided a telescopic connection shown particularly in Figs. 2, 3 and 4. This connection includes a heavy boss 46 secured to the center of a cross-strip 47 fixedly attached to the frame 10 adjacent to the center of the cot and at a point between the legs. This boss has a pivot stud 47' carrying a nut 48 which serves to bind tightly against the broad base of the boss the flat apertured end 49 of a stiff rod 50. This rod constitutes the inner section of a telescopic tie element made up of any desired number of sections which fit snugly one within the other so as to be held against relative tilting movement although capable of sliding relative to each other to a limited extent. An ordinary construction of such an element has been illustrated in Fig. 4 wherein the telescopic members of the element on rod 50

have been indicated at 51, 52 and 53. The outer member 53 has an eye 54 extending therefrom and fixed relative thereto, this eye being mounted to swing in any direction within a fork 55 depending from a carriage 56. The carriage is slidably mounted on a cross-rail 57 the length of which is substantially equal to the width of the bed B to which the cot is connected. One end of this rail is adapted to be fitted detachably beneath one of the side rails R of the bed and to be detachably clamped thereagainst by a cam 58 located where it will overlie the rail R and, when turned in one direction, will bind thereon and effect a tight connection between rail 57 and rail R. The other end of rail 57 is extended under the other side rail R of the bed and has an adjustable clamp 59 provided with a nut 60 whereby when the clamp 59 is tightened, the rail R engaged thereby will be gripped securely. Thus with the two clamping means tightened relative to the side rails of the bed, the guide or cross-rail 57 will be held against displacement relative to the frame of the bed B.

At an intermediate point rail 57 has a depressed portion 61 the lower part of which merges into one end portion of the rail 57 along an inclined portion 62.

With the guide rail 57 secured in position transversely of the bed B and with the lower section 39 of the cot legs released to permit movement of the section 36 downwardly therealong, it will be apparent that by elongating the telescopic connection and then thrusting the cot toward the bed B, the carriage 56 will travel along rail 57 and downwardly onto the depressed portion 61. This movement is effected because while there is a slideable connection between the parts 50 to 53 inclusive, there is sufficient friction set up between these parts to insure movement of the carriage 56 back onto the depressed portion 61. After carriage 56 reaches this position, the cot, which is at a low level because of the shortened legs 36-39, can roll under the bed where it will be out of the way as shown by broken lines at X in Fig. 3.

Obviously with the parts thus collapsed the cot will be out of the way. Should it be desired to set up the cot so as to support the patient while the bed is being changed, the cot is pulled outwardly to position Y in Fig. 3, thus causing the telescopic connection to elongate and bringing the carriage 56 to the full line position shown in said figure. Thereafter the cot is pulled upwardly to elongate the legs and the toothed pawls 43 act to automatically lock the legs in their elongated positions. When the top 11 of the cot has been brought to a level with the frame of the bed, said cot is pushed toward the bed so as to be held closely to it. It is to be understood, of course, that when the cot is to be used only for the purpose of supporting a patient while the bed is being changed, it will carry a pad or mattress M. With this pad or mattress in position the cot can also be used as a supplemental bed for use by a nurse or other attendant either while the cot is close to the side of the bed or while it is at a point removed therefrom. It will be noted that when the cot is pulled away from the bed as shown at Y in Fig. 3, the load thereon will be supported by the legs 36-39 and there will be no danger of the cot tilting laterally because of the rigid slideable connection between the cot and the bed.

Should it be desired to use the cot for surgical purposes, the mat or pad is removed therefrom

and the patient is placed thereon while the cot is positioned as indicated by full lines in Fig. 3. Thereafter the cot can, if desired, be pulled away from the bed and can be wheeled to any desired angle relative thereto so as to bring the patient to a point where the proper light can be had. Where a leg operation is to be performed, one or both of the legs can be strapped to the rest or rests 22 provided therefor and brought to the positions where the operation can best be performed. These rests can also be utilized for supporting the legs in upwardly extended and spread-apart positions.

After the use of the cot or table at a point remote from the bed has been completed and it is desired to restore the patient to the bed, the cot is wheeled back toward the bed while the outer member 53 is held against movement by an attendant and until the members 50, 51 and 52 are completely telescoped into the member 53. Thereafter further movement of the cot toward the bed will cause the member 53 to slide back under the bed along the rail 51 but this distance of travel will not be sufficient to bring the carriage 56 onto the inclined portion 62 of the rail. Therefore the cot will be properly supported in perfect balance against the side of the bed and thereafter the patient can readily be transferred onto the bed as will be apparent.

The top can be equipped with any suitable appliances. For example guard rails 63 having downturned ends 64 are slidable within openings in the sides of frame 10. These ends 64 can have notches 65 for receiving bolts 66 whereby, after the rails have been pulled upwardly to desired positions, the bolts can be forced into the notches, thereby supporting the rails. Thus a patient on the cot will be prevented from rolling laterally therefrom. When the rails are not in use they are pushed downwardly onto the cot so as to be out of the way.

It will be obvious of course that by reversing the position of the rail 57 across the bed the cot can be located at the opposite side of the bed than that shown.

What is claimed is:

1. The combination with a cot including a top and telescopic supporting legs connected to the top on a line extending longitudinally of the center thereof, of rigid collapsible means connected to and extending laterally from the cot,

and means for joining said collapsible means to a bed.

2. The combination with a cot including a top and telescopic supporting legs connected to the top on a line extending longitudinally of the center thereof, of rigid collapsible means connected to and extending laterally from the cot, a rail, means for detachably connecting the rail across and to the sides of a bed, and a slidable and pivotal connection between said rail and the collapsible element.

3. In a device of the class described a top, telescopic legs supporting the same, leg-rests mounted for angular adjustment both vertically and laterally relative to the top, a head-rest mounted for up and down angular adjustment relative to the top, a telescopic element extended laterally from and pivotally connected to the top at one end, and means for pivotally and slidably connecting the other end of said element to the frame of a bed.

4. In a device of the class described a top, telescopic legs supporting the same, leg-rests mounted for angular adjustment both vertically and laterally relative to the top, a head-rest mounted for up and down angular adjustment relative to the top, a telescopic element extended laterally from and pivotally connected to the top at one end, and means for pivotally and slidably connecting the other end of said element to the frame of a bed, said means including a rail, means for clamping the rail to the sides of a bed, a carriage on the rail, and a universal connection between the carriage and telescopic element.

5. In a device of the class described a top, telescopic legs supporting the same, leg-rests mounted for angular adjustment both vertically and laterally relative to the top, a head-rest mounted for up and down angular adjustment relative to the top, a telescopic element extended laterally from and pivotally connected to the top at one end, and means for pivotally and slidably connecting the other end of said element to a bed, said means including a rail, means for clamping the rail to the sides of a bed, a carriage on the rail, and a universal connection between the carriage and telescopic element, said rail having a depressed portion for receiving the carriage when shifted along the rail to one extreme position.

JULIA S. M. KNOX.
